J. T. CARMAN, OF SPRINGFIELD, ILLINOIS, ASSIGNOR TO HIMSELF, JOHN W. AND LEE W. FULTON, OF SAME PLACE.

Letters Patent No. 61,048, dated January 8, 1867.

IMPROVED BRICK MACHINE.

The Schedule referred to in these Letters Patent and making part of the same.

TO ALL WHOM IT MAY CONCERN:

Be it known that I, J. T. CARMAN, of Springfield, in the county of Sangamon, and State of Illinois, have invented a new and improved Brick Machine; and I do hereby declare that the following is a full, clear, and exact description thereof, which will enable others skilled in the art to make and use the same, reference being had to the accompanying drawings, forming part of this specification, in which—

Figure 1, sheet No. 1, is a side sectional view of my invention, taken in the line *x x*, fig. 2.

Figure 2, a plan or top view of the same.

Figure 3, sheet No. 2, a side view of the same.

Figure 4, a detached plan or top view of the brick-discharging device pertaining to the same.

Figure 5, a horizontal section of a portion of the invention, taken in the line *y y*, fig. 1.

Similar letters of reference indicate like parts.

This invention relates to a new and improved machine for moulding and pressing bricks from untempered or dry clay, and it consists in a novel and improved means for receiving and discharging the moulded clay or bricks, and in an improved means for regulating the feeding of the clay to the moulds; and also to an improved means for pulverizing or granulating the clay in order to insure it being perfectly fed to the moulds; and further, to an improved means for operating the plungers, which compress the clay in the moulds.

A represents what may be termed the base of the machine, and B is a box placed thereon, in which a semi-cylindrical grating or screen, C, is placed, and hung upon pivots, *a a*. One of these pivots, *a*, has a crank, *b*, attached, which is connected by a rod, D, with a crank-pulley, E, and through which the screen C is oscillated when the machine is in operation. F is a shaft provided with teeth, *c*, which are of curved form, and work between the bars of the screen C. These teeth are placed and keyed upon the shaft F in such a position that their ends will form two spiral rows, the teeth being of S form and placed centrally on the shaft F, as shown in fig. 1. The teeth *c* project up between the bars of the screen C a suitable distance, as shown in fig. 1, and the shaft F is rotated by a belt, G, from a shaft, *d*, on the framing H of the machine. I is an endless belt, which has buckets, *e*, attached to it, said belt working over rollers *f f*, and operated by a cross-belt, *g*, from a shaft, *h*, on the framing H. J is a hopper, which is secured to two uprights, *i i*, attached to the base A of the machine. This hopper is provided with a sliding adjustable bottom, K, the outer end of which has a pendent nut, *j*, attached, through which a screw-rod, L, passes, said rod having a toothed wheel, *k*, upon it, which gears into a corresponding wheel, *l*, on a shaft, *m*, the latter passing horizontally through the lower part of the hopper J, and having a crank, *n*, on its outer end. The shaft *h* has its bearings in the upper part of the uprights *i i*. This shaft has a toothed wheel, N, at one end of it, which gears into a pinion, *o*, on the shaft *d*, and on the opposite end of the shaft *h* there is a pulley, *p*, around which the cross-belt *g* passes. On the shaft *h* there are also keyed two pinions, *q q*, which gear into two toothed cams, O O, on the ends of a shaft, P, the latter passing through a bar, Q, to which plungers R R are attached. The ends of the bar Q are fitted and work in oblong vertical slots *r* in the uprights *i i*, and the cams O O are provided with flanges *s s*, which work between rollers *t*, placed two on the shaft *h* and two on a shaft *u*, the bearings of which are in the lower parts of the uprights *i i*. The toothed cams O O are quite irregular in form, as will be seen by referring to fig. 1, but they are of the same diameter at all points, and they are placed eccentrically on the shaft P, as shown in figs. 1 and 3. To each cam O there is attached a cam, S. These cams, S, are irregular-shaped rims at the inner sides of the cams O, and they work between pins *v v*, attached to levers T T, the upper ends of which are secured by fulcrum-pins *w* to the framing H of the machine. U U represent crescent-shaped or bow levers on the ends of a shaft, *u*, which passes horizontally through the hopper J, and have each an arm, W, attached. The lower ends of the arms W have bars X attached to them by pivots, and the outer ends of the bars X are notched to fit over the ends of a bar, Y, which rests on parallel horizontal bars Z Z. This bar, Y, works between the nut *j*, of the bottom K, and the wheel *k*, on the screw-rod L, as shown in fig. 1. The lower ends of the levers T T have slots, *b*, made in them to receive the ends of a shaft, *c*, which passes through the sides *d' d'* of a box, A', underneath the hopper J. This box, A', is open at its top and front and rear ends, and within it there is fitted a plate, B', the rear end of said plate having bars or strips *a** attached, which are bent over a shaft, *e'*, in the box, on which

they are allowed to turn or work. The rear end of the plate B' has a projection, f', extending upward and backward, as shown in fig. 1, and a plate, C', is secured transversely on the upper surfaces of the sides d' d' of the box, the plate C', when the box A' is shoved forward, being underneath moulds D', in which the plungers R R work.

The operation is as follows: The clay is introduced into the screen C, and is cut or reduced by the action of the teeth e on the revolving shaft F, and drops between the bars of said screen into the buckets e of the belt I, and is carried upward and discharged into the hopper J. As the plungers R rise from the moulds D', a result due to the toothed cams O O, working between the rollers t, the bottom K of the hopper J, which is partially withdrawn or open, is moved forward under the action of the curved levers U, which are operated by the hubs of the cams O; and the front end of the bottom K being curved or bent down, as shown at c*, the clay in front of c* is forced into the moulds D'. The plungers R then descend and press the clay in the moulds, the plate C' on the box A' serving as a bottom for the moulds. Where the plungers R reach a certain point, the termination of their pressing movement, the pressure of the plungers is slackened or eased, and the box A' is drawn backward, under the action of the levers T T, and the plate C' is withdrawn from underneath the moulds and the pressed clay or bricks therein, and the plungers R descend and expel the bricks from the moulds, discharging them upon the plate B'. The box A' then returns, the plate C' clearing off the bottoms of the moulds and the plate B' discharging the bricks, the plate tilting as it passes out from underneath the moulds, as shown clearly in fig. 1. As the plungers R make their final downward movement, the lines of the cams O act upon the levers U, and the bottom K of the hopper J is moved back to admit of another quantity of clay to pass down in front of the bent end c* of the bottom K. The plungers R then rise and the operation is repeated. The quantity of clay fed into the moulds is regulated by adjusting the bottom K of the hopper J through the medium of the rod m, pinions l k, screw-rod L, and nut j.

Having thus described my invention, what I claim as new, and desire to secure by Letters Patent, is—

1. The sliding box A', provided with the plate C', in combination with the fixed moulds D' and the plungers R, all arranged to operate in the manner substantially as and for the purpose set forth.
2. The sliding bottom K, operated substantially as shown, in combination with the fixed moulds D', plungers R, and the plate C' on the sliding box A', substantially as and for the purpose specified.
3. The adjusting of the bottom K to regulate the supply of clay to the moulds through the medium of the rod m, pinions l k, screw-rod L, and nut j, substantially as set forth.
4. The pulverizing or reducing of the clay by means of the oscillating screen C, and the teeth e on the rotary shaft F, substantially as shown and described.
